UNITED STATES PATENT OFFICE.

FRANK H. HULSCHER, OF ATLANTA, GEORGIA.

MANUFACTURE OF SHEET-METAL BLANKS.

1,301,700.

Specification of Letters Patent. Patented Apr. 22, 1919.

Application filed September 29, 1917. Serial No. 184,048.

To all whom it may concern:

Be it known that I, FRANK H. HULSCHER, a citizen of the United States, residing at Atlanta, in the county of Fulton and State 5 of Georgia, have invented new and useful Improvements in the Manufacture of Sheet-Metal Blanks, of which the following is a specification.

This invention relates to the manufacture 10 of sheet metal blanks, and the object is to produce from one sheet, a blank which may be pressed into proper form for the manufacture of a shuttle designed to carry a bobbin and to be used in a loom.

15 A further object is to form a blank of such construction that when pressed into shape to form a device of the character indicated, said device shall comprise integrally formed side members, and end members, portions of 20 which are of substantially rectangular cross section and portions of which are tapered to form a conical nose portion.

25 A further object is to provide a blank including portions formed integrally therewith for retaining a bobbin in position in a shuttle manufactured from the blank having the configuration herein described.

30 A further object is to provide means for stiffening certain of the members of the blank by producing therein longitudinally extending corrugations.

35 A still further object is to form a blank in such manner that when pressed into shape it shall include in connection with the structure above specified, means for guiding the thread leading from the bobbin, and means for retaining the bobbin in position.

40 With the foregoing and other objects in view, the invention consists in the novel construction, combination and arrangement of elements hereinafter described and claimed.

In the accompanying drawings:

Figure 1 is a plan view of the blank.

45 Fig. 2 is a plan view of the shuttle formed from the blank after the members thereof have been bent into proper position.

Fig. 3 is a view of the shuttle in longitudinal section, the end portions being in elevation.

50 Fig. 4 is a transverse section through that portion of the shuttle wall or walls engaging the bobbin.

The blank consisting of sheet metal and preferably of sheet steel includes a plurality 55 of longitudinally extending members 10 and 12, these members being corrugated in a di-

rection lengthwise of the blank as a whole and the corrugations terminating at or about the point 14. Each side member 10 and 12 is inwardly deflected for the purpose of 60 forming bobbin engaging devices designated 15 and 16, these devices comprising a plurality of vertically extending ribs with slots between the ribs. This structure is more fully shown in Fig. 4 and the bobbin engaging 65 devices are formed by stamping after the blank shown in Fig. 1 is formed, but may be formed incidentally to the production of the blank itself.

Between the longitudinal members 10 and 12 of the blank and at one end of the latter is a tongue 17 formed by slotting the blank at 18 and 19, this tongue being deflected inwardly when the blank is bent into position for forming a shuttle. Extending laterally 75 from the end portions 10 and 12 are members 20 and 21 each provided with a tongue, one of these being designated 22 and the other 23, the tongue last named co-operating with the tongue 17 when the blank is 80 bent into position as above indicated.

The opposite end of the blank is of similar configuration in general outline, but the corrugations extend to the line 25 which may be termed a base line from which the 85 tapered end portions 26, 27 and 28 project. These tapered portions are separated by corresponding tapered openings 29, 30 reversely arranged with reference to the tapered members 26, 27 and 28. Lateral extensions 30' 90 and 31 correspond in position with the members 20 and 21 at the opposite end of the blank but the members 30' and 31 are not separated from the body portion of the blank, but are to be deflected along the lines 95 32 and 33 in the formation of the shuttle.

Each of the lateral extensions 30', 31, 20 and 21, is provided with a tapered portion 34, and these tapered portions and the elements forming the base thereof meet along 100 a line centrally of the bottom of the shuttle, and the meeting edges are secured by welding, the meeting edges of the tapered portions being likewise connected for the purpose of forming substantially continuous 105 end portions.

An aperture 40 in one side member is connected by a slot 41 with an aperture 42 having communication with the cutaway portion 43. This cutaway portion 43 extends 110 into the tongue 44 projecting between the longitudinally extending members 10 and

12 and terminates with an aperture 45. The thread passing through the apertures and slot rests in the aperture 45 and passes thence across a horizontally extending member 46
5 carried by the tongue 44. This member 46 supports the thread between the aperture 45 and aperture 40 and the necessary degree of tension on the thread is secured.

The member 10 is provided with a longitudinal slot 11 for the accommodation of a feeler of the type employed for automatically effecting a change of bobbins when the thread is becoming exhausted.

What is claimed is:

- 15 1. As an article of manufacture, a blank comprising a plurality of longitudinally extending members spaced apart and providing a longitudinal opening, said longitudinally extending members terminating in tapered portions and said blank being provided with a tapered portion at each end opposite the ends of the opening, and said blank being provided with a tongue projecting into one end of the opening and cut 25 away to form thread guiding means.
2. As an article of manufacture, a blank comprising a plurality of longitudinally extending members spaced apart and connected at their ends, said connecting portions and 30 said longitudinally extending members being provided with tapered portions, and said blank including laterally extending members carrying tapered portions having substantially one-half the dimensions of the 35 tapered portions first named, and said blank including a tongue projecting into the opening and provided with thread guiding means.
3. As an article of manufacture, a blank 40 comprising a plurality of longitudinally extending members connected at their ends, the blank terminating at each end in a plurality of tapered portions, the ends of the tapered portions being equally spaced apart, 45 and said blank including inwardly extending devices forming ribs extending transversely of the longitudinally extending members.
4. As an article of manufacture, a blank 50 comprising a plurality of longitudinally extending members, one of said members having a longitudinal slot therein, and said members being spaced apart to form a longitudinal opening, the blank including a tongue projecting into one end of the opening 55 and provided with a cutaway portion forming thread guiding means, said blank

including a diagonally extending slot communicating with an aperture formed in one of the longitudinally extending members, and said tongue being slotted to form a member adapted to be deflected at an angle with the tongue. 60

5. As an article of manufacture, a blank having an approximately central longitudinally extending opening and a tongue projecting into said opening and having its edges separated from the adjacent edge portions of the blank proper, said tongue being slotted longitudinally to form a member adapted to be deflected at an angle with the 70 tongue. 65

6. As an article of manufacture, a blank provided with an approximately centrally located opening extending longitudinally and with a plurality of tapered portions 75 equally spaced at each end of the blank, the tapered portions at the opposite sides of the blank being of substantially one-half the dimensions of the tapered portions intermediate thereof, and a tongue carried by the 80 body portion of the blank and projecting into the opening therein.

7. As an article of manufacture, a blank provided with an approximately centrally located opening extending longitudinally 85 and with a plurality of tapered portions equally spaced at each end of the blank, the tapered portions at the opposite sides of the blank being of substantially one-half the dimensions of the tapered portions intermediate thereof. 90

8. As an article of manufacture, a blank comprising a plurality of longitudinally extending members each provided with a series 95 of slots extending transversely thereof, said members being spaced to form a longitudinal opening, the blank including a tongue projecting into one end of the opening and provided with a cutaway portion forming an elongated opening with curved edge portions and with thread guiding apertures oppositely located near certain of the meeting edges of the opening, the blank being scored along a line intersecting others of the meeting edges, and the blank being provided with 100 a diagonal slot communicating with one of the thread openings and extending partly through one of the aforesaid longitudinal members. 105

In testimony whereof I affix my signature. 110

FRANK H. HULSCHER.
